UNITED STATES PATENT OFFICE.

WILLIAM G. BLAUVELT, OF NEW YORK, N. Y., ASSIGNOR TO AMERICAN TELEPHONE AND TELEGRAPH COMPANY, A CORPORATION OF NEW YORK.

TELEPHONE-EXCHANGE SYSTEM.

Application filed July 15, 1927. Serial No. 206,088.

This invention relates to telephone exchange systems, and more particularly to such systems wherein telephone connections are established by means of mechanical 5 switching devices.

The invention is in the nature of an advancement in the art of automatic switching devices, and has for its object the provision of new and improved methods of and means 10 for establishing telephone connections automatically.

In attaining this object the invention employs the general idea of a common driving mechanism, in conjunction with a plurality 15 of mechanical operators or plug carriers which serve the terminals of trunk lines located in a screen type terminal bank.

According to the general aspect of the invention, a team of mechanical operators or 20 plug handlers is provided, one on either side of the multiple frame, adapted to serve plugs individual to the trunk lines incoming to the terminal bank in such a manner that a plug individual to a trunk on which a call has 25 been initiated is removed from its normal seat, carried across the face of the terminal bank and inserted at the crossing points of the particular incoming trunk and an idle outgoing trunk of a desired group. To effect 30 this operation a finder carriage, to which a plug handling device is removably associated, is moved vertically by means of a power belt to which it is permanently secured, over the plugs of a group of incoming 35 trunks until the plug associated with a calling incoming trunk is reached, whereupon a pantograph, secured to a vertical bridge or frame, is actuated to cause the plug handler to seize the selected plug; the pantograph then 40 restores, and the plug handler withdraws the plug from its normal seat, whereupon the vertical bridge is moved horizontally across the terminal bank, carrying the plug handling device to the terminals of an idle trunk in 45 a desired group of outgoing trunks. The pantograph is then re-actuated to cause the plug handler to expel the plug and insert it in the multiple bank at the point of intersection of the incoming trunk and a selected 50 idle outgoing trunk. Following the establishment of the connection the plug handler is reassociated with the finder carriage and placed in readiness to serve other incoming trunk plugs. At the termination of a set up 55 connection and when a calling subscriber re-

leases the incoming trunk, the equipment heretofore employed in placing the plug in the multiple bank, is re-actuated in a certain sequence, to cause the plug to be removed from the multiple and returned to its normal seat.

In the preferred embodiment of the invention there are twenty movable plugs, a plug on one side of the bank being paired with a plug on the opposite side of the bank to 60 serve as a selector switch, so that each frame comprises a group of twenty selectors, each selector having two plugs. When the incoming trunks are idle the plugs are located in plug seats on one end of the multiple 65 bank. A team of two plug carriers is provided for every twenty incoming trunks, one operator on each side of the frame. The power for operating the apparatus is supplied through a continuously revolving main 70 shaft keyed to which are a plurality of beveled gears. Idler gears are carried on magnet armatures and may be meshed with the main shaft gears for operating steel power belts to which are attached the finder 75 carriage for vertical motion, and the movable bridge for horizontal motion.

A particular feature of the invention resides in the provision of a circuit arrangement whereby one of a team of plug carriers, 80 upon reaching a certain stage in extending a connection, causes another plug carrier to be placed in position to handle the next call incoming to the terminal bank.

This feature is effected by a certain series 85 relation between several cams of the sequence switches associated with the plug carriers whereby a sequence switch employed in setting up and taking down a connection waits in the "waiting allotment" position until 90 another plug carrier reaches a certain stage in extending another connection whereupon 95 it is moved into the "allotted" position to be employed in the next connection.

Another feature of the invention resides 100 in the provision of a manually operated key for each mechanical operator, the actuation of either of which causes the carrier associated therewith to be rendered inactive to extend calls incoming to the terminal bank but 105 allows it to take down connections it has already been instrumental in setting up.

A thorough understanding of the switching mechanism embodying the above and other features of this invention and its operation, 110

will be had from the following detailed descriptions made with reference to the accompanying drawings, in which:

Figure 1 is a front view of the screen type terminal bank, schematically represented, and its associated switching mechanism;

Fig. 2 is an end view of the switch partly in section taken along the line 2—2 of Fig. 1 and looking in the direction of the arrows;

Fig. 3 is a sectional view of the switch taken along the line 3—3 of Fig. 1, looking in the direction of the arrows, and shows the equipment on both sides of the switch frame;

Fig. 4 is a sectional view taken along the line 4—4 of Fig. 1 and looking in the direction of the arrows;

Fig. 5 is a fragmentary view of a portion of the switching mechanism showing the finder carriage and the manner in which the plug carrier is associated therewith;

Fig. 6 is a side view of the plug carrier or plug handling device in its normal position;

Fig. 7 is a plan view, partly in section, of the plug handling device in normal position, showing its position relative to that of a plug resting in its seat on one end of the multiple;

Fig. 8 is a side view of the plug handler when in engagement with a plug, prior to the removal of the plug from its seat;

Fig. 9 is a plan view of the plug handler in the same position as shown in Fig. 8;

Fig. 10 is a plan view of the plug handler after having removed a plug from its seat;

Fig. 11 is a fragmentary section of the ratchet wheel which is a part of the plug handling device;

Fig. 12 is a partial top view of the multiple bank showing a plug inserted on each side of the bank and the manner in which the plugs are supported in the multiple.

Fig. 13 is an end view of the multiple bank as disclosed in Fig. 12;

Fig. 14 is a top view of the multiple showing a plug on the right, in its normal seat and its associated off-normal springs operated, and the plug on the left withdrawn from its seat and its associated off-normal springs in normal position; and

Figs. 15 and 16 are the electrical circuits employed in connection with the switching mechanism.

The first detailed description will be directed to the switch structure in general, with an exact enumeration of the various elements which go to make up the switch, their relation to each other and their construction. The second description will embody the workings of the electrical circuits which are employed in effecting the operation of the switch.

Like numerals indicate similar elements throughout the several views.

Referring in general to Fig. 1 and Fig. 2,

the screen type multiple bank 100 is mounted on the switch frame in any suitable manner. The screen type multiple bank, as the name implies, is a screen of vertical and horizontal wires woven in a manner similar to window screen, except that the horizontal and vertical wires are insulated from each other. Three screens are clamped together in parallel planes to form a bank. The horizontal wires of the multiple extend through under the plugs 101 and off-normal springs 104, and are connected to the terminal strips 231 of the finder bank 102, as shown in Fig. 14. The vertical wires of the outer screen extend below the bottom of the lower multiple frame member and are connected each one to an individual commutator segment S (see Fig. 15) and are used in trunk hunting as will hereinafter appear.

Connections through the multiple are made by plugs 101, which, inserted at any cross point, connect the tip, ring and sleeve wires of an incoming trunk respectively to the tip, ring and sleeve wires of an outgoing trunk. Figs. 12 and 13 clearly show the manner in which these connections are made, as does the schematic representation of the plug in Fig. 15. It will be noted that the horizontal wires are bared, and the vertical wires insulated, the insulation being cut away at the cross points to expose the wires to the plug contacts.

When the plugs are in their respective seats, they are supported as shown in the upper portion of Fig. 7 and also in Fig. 13. Each plug is provided with a slot which engages the extended portion or flange of the frame piece 230, and its spring contacts engage the horizontal wires between the first set of vertical wires and the frame member 230.

The power for operating the apparatus is supplied through a continuously revolving main shaft 107 on either side of the switch frame. Keyed to each shaft 107 are six bevelled gears 108, 109, 110, 111, 112 and 113. Idler gears 114, 115, 116, 117, 118 and 119 are carried on the armatures of magnets 120, 121, 122, 123, 124 and 125, respectively, which, upon operating, cause their associated idler gears to mesh with the main shaft gears to perform functions as will hereinafter appear.

Upon the operation of magnet 120 (Fig. 2), the idler gear 119 meshes with the main shaft gear 113 and also with the gear 126 associated with the sequence switch 127. The operation of magnet 121 causes idler gear 118 to mesh with main shaft gear 112 and also gear 128 to mesh with the gear wheel 129, whereupon the power from the main shaft 107 is transmitted to the countershaft 130, on which a pulley for the power belt 131 is rigidly mounted. The front half of the power belt 131 thereupon is moved from left to right,

assuming the main power shaft 107 to be rotated in an anti-clockwise direction, when looked at from the top. The purpose for this movement of the belt 131 will hereinafter be set forth. In like manner, the operation of magnet 122 causes the idler gears 117 and 132 to mesh with gears 111 and 333, respectively, the former associated with the power shaft 107 and the latter with shaft 130, so that the belt 131 in this case is moved from right to left. Upon the operation of magnet 123, idler gears 116 and 133 mesh with gears 110 and 134, respectively, to cause the power from shaft 107 to be imparted to shaft 135, on which a pulley 136 for the power belt 137 is securely mounted. Thereupon the belt 137 is moved downward. In like manner, the meshing of gears 115 and 138 with gears 109 and 134, respectively, causes the belt 137 to be moved upward upon the operation of magnet 124. The purpose of these movements of power belt 137 will appear from later description.

When magnet 125 is operated, gears 114 and 139 mesh with gears 108 and 140, whereupon the shaft 141 on which the gear 140 is mounted, rotates, causing the cams 171 and 172 secured thereto, to impart a downward movement to the blade 173, against the action of restoring springs 210 and 211. The blade 173 extends across the top of the frame and is rotatably mounted at the points 300 and 301.

Attached to the power belt 137, at 212, is a finder carriage 142 which rides on rollers along the vertical guides 143. Attached to the carriage 142 is a set of contact brushes 144 which travel over the contacts in the finder bank 102, in search of a particular incoming trunk, as will hereinafter be described. During the process of finding, a plug handler, or mechanical operator 145, is coupled to the finder carriage 142 and is moved upward or downward with it as the power belt 137 is moved. To effect this coupling, the carriage 142 is provided with two extending pegs 213 and 214 which fit into corresponding holes 215 in the plug handler, as shown in Fig. 5. A centering roller 146 used for centering the carriage 142, rides in a corrugated rack 147 and is attached to the carriage 142 just above the finder brush 144. When power is applied to the vertical belt 137 by the operation of the armature of magnet 124, the idler gear 115 is brought into mesh with the main shaft gear 109, and gear 138 with gear 134 whereupon shaft 135 rotates and the power belt 137 moves the finder carriage 142 upward. In the process of finding, magnet 124 is deenergized and its armature restores just before the centering roller 146 drops into a slot in rack 147, so that the final movement of the carriage is controlled by the centering roller 146. This insures perfect alignment of the plug handler and the contacts of a calling incoming trunk in the finder bank.

Attached to the horizontal power belt 131 at the point 153 is a movable bridge or vertical frame which comprises the guide rails 151 and 152 which are fastened together by the two cross pieces 154 and 155 and on which the rollers 156, permanently secured to the plug handler 145, ride. Secured to the guide 151 is a corrugated centering piece 157 over which the centering roller 158, which is secured to the plug handler 145 rides, insuring perfect alignment of the plug handler with the plug before the former is actuated to seize the plug. The frame or bridge is provided with a roller 358 at the bottom, which rides on the horizontal rail 159, and a similar roller 161 (Fig. 3) at the top, which rides on the guide rail 160. The guide rails 159 and 160 provide for the horizontal movement of the bridge across the multiple bank. As hereinbefore stated, the plug handler 145 is removably associated with the finder carriage 142, as shown in Fig. 5.

Attached to the bottom of the vertical bridge member 152 nearest the frame is a set of contact brushes 167. These brushes make contact with the commutator segments of commutator 168 as the bridge is moved over the multiple, for a purpose to be described hereinafter.

A pantograph comprising the vertical member 164 and the two horizontal members 165 and 166 is pivotally mounted on the vertical bridge, the vertical member 164 bearing against a roller 169 on plunger 170 of the plug handler 145. The pantograph is carried by the bridge in its movements across the multiple. The pantograph is operated when the armature of magnet 125 is actuated to cause idler gears 114 and 139 to mesh with gears 108 and 140, respectively. The meshing of gears 139 with gear 140 causes the shaft 141 to rotate, whereupon the cams 171 and 172 mounted thereon drive against the blade 173 which extends the entire length of the frame, and causes it to engage projection 174 of the pantograph and move it downward, so that the vertical member 164 rides on the roller 169 and forces the plunger 170 of the plug handler 145 inward to effect a seizure or deposit of a plug 101 as will next be described.

The plug handler 145 consists of a frame 177 provided with a slot 278 in which a plunger 170 is adapted to move under the camming action of the vertical member 164 of the pantograph, on the roller 169. A spiral spring 175 holds the plunger in normal position, as shown in Figs. 6 and 7. Pivotally mounted on the plunger 170 by means of a screw 178 is a ratchet wheel 179 which comprises two camming surfaces 180 and 181 and two stops 182 and 183, the camming surfaces also acting as stops for engagement with the ratchet pawls 184 and 199 which are secured to the frame 177. When the plunger 170 is forced inward the ratchet wheel moves with the

plunger in the same direction and the ratchet pawls engage the stops to cause the wheel to rotate during its sliding movement. Also pivoted to the plunger 170 at 194 is a plug pawl 185 having a hooked end adapted to engage a correspondingly hooked end of the plug 101. Normally, as shown in Fig. 7 the plug pawl rests on the cam 180 and is raised in the position shown.

10 When the plunger 170 is forced inward due to the actuation of magnet 125 and the subsequent action of the pantograph, the ratchet wheel 179 being attached thereto moves in the same direction, sliding bodily over the frame 177. The ratchet pawl 184 engages the stop 182 causing the ratchet wheel 179 to turn less than a quarter turn due to the length of the inward stroke of the plunger, during which interval the plug pawl 185 rides off cam 180 and drops into the position shown in Figs. 8 and 9 under the action of spring 200. The hooked end of the plug pawl 185 thereupon engages the hooked extended portion of plug 101.

25 When the plug 101 is engaged by the plug pawl 185 and magnet 125 deenergized, as will appear from a later circuit description, the pantograph is returned to normal and the plunger 170 is forced outward under the restoring action of spring 175, which was compressed when the plunger was forced inward. The plug pawl 185 in moving outward with the plunger 170 removes the plug 101 from its normal seat. The plug 101 is now in the position shown in Fig. 10, its hook end resting in the slot 278 and engaged by the hook end of the plug pawl 185. On the outward movement of the plunger 170, the pawl 199 engages the stop 183, causing the ratchet wheel to 30 complete the quarter turn started on the inward stroke of the plunger, so that the ratchet wheel assumes a position similar to that shown in Fig. 6, except that cam 180 occupies the position of stop 183 and cam 181 that 35 of stop 182.

50 The plug handler must now deposit the plug at another position in the multiple. In the description of the operation of the switch to follow, it will be pointed out how the plug 55 handler after removing the plug from its seat is carried across the multiple to the terminals of an idle trunk, and for simplicity it will now be assumed that this operation has been effected. The magnet 125 is again operated, causing the pantograph to function and force the plunger 170 of the plug carrier inward. It will be noted that when the plug is in the act of grasping a plug in its seat, the plunger 170 requires a relatively short 60 stroke as the plug when in its seat is nearer the plug handler than when it is in a position in the multiple bank. To provide for this necessity, the blade 173 is provided with a raised portion 201 immediately above the 65 home position of the plugs. This results in

a short stroke of the plunger 170 at this position and a subsequent smaller rotation of the ratchet wheel 179 as just described. At positions over the outgoing trunk terminals the blade 173 is not provided with raised portions, so that the plunger has a longer stroke at these positions and consequently the ratchet wheel turns a greater distance, and in reality a full quarter turn as will now be described. 70

75 The ratchet pawl 199 is now in engagement with stop 183 and pawl 184 with cam stop 181. As the pantograph causes the plunger 170 to be moved inward due to the re-actuation of magnet 125, the ratchet wheel 179 turns a full quarter turn. As the ratchet wheel turns, the cam 181 rides under the plug pawl 185 and starts to raise it out of engagement with the plug. The cam has been so designed that the plug pawl is free of the plug before the hooked portion thereof leaves the slot 178 and after the plug springs have engaged the trunk wires. In this manner the plug is insured against falling. The plunger in continuing its inward stroke forces the plug further into the multiple until a position as shown in Fig. 12 is reached. The cam 181 now occupies the position of cam 180 in Fig. 6 and the cam 180 and stops 182 and 183 occupy corresponding positions, and the ratchet wheel itself is positioned at the further end of the frame 177 so that the ratchet pawls will be resting on the sides of stops 182 and 183. 85

90 When the pantograph is again restored to normal under the action of spring 350, the plunger 170 is again forced outward under the action of spring 175, whereupon the ratchet wheel 179 slides back into the position shown in Fig. 6, but it is not rotated, the several cams and stops assuming the positions 95 just given them in the previous paragraph. 100

105 The electric circuit again functions and the plug handler is carried back on the vertical bridge across the multiple and is again connected to the finder carriage. 110

115 After a call has been completed and the incoming trunk released, a complete cycle of operations similar to those just described, but in a reverse order, is performed, whereby the plug employed in the establishment of the connection is removed from the multiple and returned to its seat, and since these operations are identical with those described, it is believed unnecessary to repeat the description. 120

125 A set of contacts 188 is carried by the plug handler, the contacts being normally held open due to a camming action of the plug, so that the contacts are closed between the time a plug is deposited in the multiple bank and picked up again by the plug handler. 130

Secured to the finder carriage is a tripping mechanism 512 having extending portions 598 and 599 which engage the transfer switch 510 at certain times during the travel of the carriage. The tripping element 512 is so pro-

portioned relative to the distance traveled by the carriage 142 that when the carriage reaches its uppermost position on its upward travel, the extension 598 engages and throws the switch 510 to cause a circuit change, whereby the carriage is immediately started on its downward travel. The extension 598 does not override the switch 510, so that it does not re-actuate the switch when the carriage starts down. The extension 599 of the tripping mechanism is provided to cause the carriage 142 to be started upward when it reaches its lowermost position on its downward travel.

The detailed operation of the system disclosed is as follows, particular reference being made to Fig. 15 and Fig. 16, the former being placed immediately above the latter in tracing the circuits: Assuming that a call has been initiated by a subscriber at a distant substation and the call has been extended to the incoming trunk 500, it will be now described how the connection is further extended to an outgoing trunk, such as 501. When the trunk 500 was selected for use, the connection, which has so far been set up in the usual manner, will cause the sleeve 502 of trunk 500 to be grounded. A circuit is thereupon established extending from battery, winding of relay 503, right-hand winding of relay 504, contact N-2 of the off-normal springs 106 located at the front of the multiple bank, contact N-1 of the off-normal springs 106 located at the rear of the terminal bank to ground on the sleeve wire 502 of trunk 500. Relays 503 and 504 operate in series in this circuit. Relay 504 in operating locks up to ground on the sleeve 502 by way of its left-hand winding, front contact and inner left-hand armature and conductor 505. At its outer left-hand armature and front contact, relay 504 causes battery to be connected to the contact 506 of the finder bank over a circuit extending from battery through resistance 507, contacts N-4 and N-3 of off-normal springs 106, front contact and outer left-hand armature of relay 504, conductor 508 to the contact 506 of the finder bank.

Relay 503 in operating connects ground to the start lead 509 which causes start relay 600 to operate over an obvious circuit. Assuming the sequence switch 127 (Fig. 1) to be in position 1, which will be the case when neither of the mechanical operators on the front or rear of the bank frame is in use, a circuit is established extending from ground, front contact and armature of start relay 600, normal contact of key 601, G cam of sequence switch in position 1, conductor 603, back contact and middle left-hand armature of relay 604, conductor 605, right hand winding of relay 606 to battery and ground. Relay 606 operates in this circuit and locks in a circuit extending from battery, right-hand winding of relay 606, inner right-hand arm-

ture and front contact of relay 606, conductor 607, I cam of sequence switch in positions 1 to 2, conductor 608 to ground by way of back contact and inner left-hand armature of relay 609. At its inner left-hand armature and front contact, relay 606 completes a circuit extending from ground, inner left-hand armature and front contact of relay 606, conductor 610, D cam of sequence switch in position 1, winding of sequence switch magnet 120 to battery and ground. The operation of magnet 120 in this circuit causes the gear 119 to mesh with the drive shaft gear 113 and sequence switch gear 126, whereupon the sequence switch moves into position 2. In position 2 a circuit exists extending from ground on the back contact and outer left-hand armature of relay 609, outer armature and front contact of relay 606, cam J of sequence switch in position 2, conductor 612, contact 613 of transfer switch 510, winding of updrive magnet 124 to battery and ground. It will be noted that the contacts 613 of transfer switch 510 will be closed at this time as the tripping element 512 carried by the finder carriage 142 will be at its lowermost position, having opened the downdrive contacts 614 on a previous movement of the carriage 142. The mechanism is so arranged that carriage 142, after having served a particular incoming trunk, remains at the level of the trunk served, so that when called upon to set up or take down another connection on a trunk at a level below that at which it is resting, it will be moved upward until the transfer switch 510 is actuated to send the carriage downward in search of the trunk requiring service. Upon energization, updrive magnet 124 causes idler gears 115 and 138 to mesh with drive shaft gear 109 and gear 134, respectively, whereupon shaft 135 is rotated and power belt 137 to which the finder carriage 142 is attached, is moved vertically, so that the finder brushes 514, 515 and 516 of the brush set 144 are moved vertically and test over the finder bank contacts. Under this condition the finder hunts for battery on the bank contacts and finds it on contact 506 as hereinbefore described, whereupon relay 609 operates in a circuit extending from contact 506, brush wiper 516, conductor 517, L cam of sequence switch in position 2, conductor 615, left-hand winding of relay 609, O cam of sequence switch in position 2 to ground.

It will be noted here that relay 609, in operating, as just described, removes ground from the operating circuit of the updrive magnet and the vertical movement of the carriage is arrested and the brushes 514, 515 and 516 are positioned on corresponding finder contacts for trunk 500. Relay 609 also opens the locking circuit for relay 606 which thereupon restores. Relay 606 in restoring causes the sequence switch magnet 120 to op-

erate in a circuit extending from ground on the inner left-hand armature and back contact of relay 606, D cam of sequence switch in position 2, winding of magnet 120 to battery and ground. Magnet 120 on energizing causes the sequence switch to be moved into position 3. In moving from positions 2 to 3, the sequence switch causes the plug magnet 125 to operate in a circuit extending from battery and ground, winding of plug magnet 125, cam C of sequence switch in position 2½ to 3, conductor 699, innermost left hand armature and back contact of relay 604, to ground by way of the E cam of the sequence switch. 70

Upon the operation of plug magnet 125 gears 114 and 139 mesh with drive shaft gear 108 and gear 140, respectively, whereupon shaft 141 is rotated, causing the cams 171 and 172 to engage the blade 173 and force it downward, the raised portion 200 engaging extension 174 of the pantograph, whereupon the vertical member 164 forces the plunger associated with the plug handler inward, to seize the plug associated with the incoming trunk 500 in a manner hereinbefore described. Relay 609 releases when the sequence switch moves out of position 2. When the finder on the front of the frame has found the calling trunk and the corresponding plug has been lifted, the off-normal springs associated therewith are actuated, N-2, N-4, ON-2 and ON-4, being operated. N-2 opens the circuit to the operating windings of relay 504 and relay 503. Relay 504 remains operated to ground on sleeve 502, through its locking winding. Relay 503 releases. N-4 removes battery from the finder bank terminal 506. 75

The circuit equipment is now awaiting the sender. Relay 606 now operates in a circuit extending from grounded battery, left-hand winding of relay 606, J cam of sequence switch in position 3, conductor 616, finder brush 514 and its associated finder contact, tip conductor of trunk 500, over the fundamental circuit to the sender in the usual manner, ring conductor of trunk 500, contact and brush 515 of the finder, conductor 617, cam H of sequence switch in position 3, conductor 618 to ground over the back contact and outermost left-hand armature of relay 604. Relay 606 locks over its inner right-hand armature and front contact, conductor 607, cam I of sequence switch in position 3, conductor 616, tip of trunk 500, over the fundamental circuit to the ring conductor of trunk 500, H cam of sequence switch in positions 3 and 4, conductor 618, back contact and outermost left-hand armature of relay 604 to ground. When relay 606 operates, the sequence switch magnet 120 is energized in a circuit extending from ground, inner left-hand armature and front contact of relay 606, conductor 610, D cam in position 3, winding of magnet 120 to battery and ground. The sequence switch is now moved into position 4. When the sequence switch moves out of position 3, the circuit for the plug magnet 125 is opened, whereupon this magnet restores, permitting 80 the blade 173 to return to normal under the restoring action of springs 210 and 211. The pantograph thereupon restores and the plug handler plunger is forced outward, causing the removal of the plug from its seat as hereinbefore described. 85

With the sequence switch in position 4, relay 609 operates in a circuit extending from grounded battery, cam O in positions 3 to 11, left-hand winding of relay 609, conductor 615, cam L in position 4, conductor 610, front contact and inner left-hand armature of relay 606 to ground. Relay 609 at its inner left-hand armature and front contact connects ground to conductor 619, thence to cam M in position 4, conductor 620, winding of selector power magnet 121, to battery and ground over the back contact and armature of plug magnet 125, whereupon selection begins. The operation of selector magnet 121 causes the gears 118 and 128 to mesh with power gear 112 and gear 129, respectively, whereupon the power belt 131 to which the vertical bridge 152 is attached, is moved from left to right. The bridge, carrying the plug handler thereupon moves across the multiple bank. 90

As the selector moves over the multiple, the brush set 167 also carried by the bridge, moves over the face of the commutator 168. 100 The brush riding on the commutator segments B, causes ground connected to this brush to be sent back by way of the commutator segments B, conductor 522, cam I of sequence switch in position 4, conductor 616, 105 thence over the tip conductor of trunk 500 to short circuit the stepping relay of the sender in a manner well known in the art. When the sender has been satisfied, the fundamental circuit is opened and relay 606 releases. Relay 609, however, remains operated since it is locked up first over its front contact and inner right-hand armature, conductor 23, cam N in positions 4 and 5, conductor 624 to the sleeve segments S of busy 110 trunks, and second from its front contacts and outer right-hand armature, conductor 621, K cam in positions 4 and 5, conductor 622, brush and C commutator segments to ground. There is therefore no pause between group selection and trunk hunting. The bridge continues to move across the multiple, therefore, until an idle trunk such as 501 is encountered. 115

When the idle trunk 501, characterized by 120 the absence of ground on its sleeve segment S, is encountered, relay 609 loses its sleeve locking circuit and then its locking circuit from the C commutator when the plug is centered. When relay 609 restores its ar- 125 ma- 130

tures, the energizing circuit for selector magnet 121 is opened and the vertical bridge comes to rest. On releasing, relay 609 also connects ground by way of its back contact and inner right-hand armature, conductor 623, cam N in positions 4 and 5, conductor 624, brush and commutator segment S individual to trunk 501 to the sleeve thereof. This ground renders the trunk 501 busy. At 10 its inner left-hand armature and back contact relay 609 connects ground to the conductor 608, conductor 625, cam F in position 4, winding of sequence switch magnet 120 to battery and ground. Magnet 120 in operating in this circuit causes the sequence switch to move from position 4 to position 6.

As the sequence switch moves from position 4 to position 5, the plug magnet 125 is energized in a circuit extending from ground 20 on the E cam in positions 1 to 15, innermost left hand armature and back contact of relay 604, conductor 699, C cam of sequence switch in position 4½ to 5, conductor 519 to battery and ground through the winding of plug 25 magnet 125. The actuation of plug magnet 125 again causes certain mechanical elements to function as hereinbefore described, to cause the plug handler to force the plug into the screen multiple. Now the connection has 30 been completed and the plug, as schematically shown at 523, connects the tip, ring and sleeve conductors of trunk 500 to the tip, ring and sleeve conductors, respectively, of trunk 501 by way of the horizontal wires 35 525. In position 6 of the sequence switch, the circuit for plug magnet 125 is opened so that the plug handler plunger 170 is forced away from the multiple leaving the plug in the multiple, and the return magnet 40 122 is operated in a circuit extending from grounded battery, armature and back contact of plug magnet 125, winding of return magnet 122, conductor 527, cam M in positions 6 and 13, conductor 628, to ground on 45 the commutator segment M and its associated brush. Magnet 122 causes certain mechanical functions as hereinbefore described to cause the selector bridge to return to normal. As the bridge returns to normal, the brush at the same level as commutator segment M rides on this segment and consequently magnet 122 remains operated until 50 the brush leaves the M segment and rests on the Y segment of the commutator.

55 At the termination of a call the ground on the sleeve wire 502 of trunk 500 will be removed in a well-known manner, causing the locking circuit for relay 504 to be opened, whereupon this relay restores. Relay 504 in releasing connects ground to the finder bank terminal 506. The circuit may be traced from ground, ON—4 spring on front of frame, back contact and outer left armature of relay 504 to bank terminal 506. Ground is also 60 connected to the disconnect lead 529 from the

right-hand armature and back contact of relay 504, ON—2 spring on front of frame, and thence to cam H in positions 18 to 1 and positions 7 to 8, conductor 626, back contact and outer left-hand armature of relay 606, 70 right-hand winding of disconnect relay 604, to battery and ground. Relay 604 operates in this circuit and locks through its front contact and innermost left-hand armature to ground on the E cam in positions 1 to 75 15. A circuit now exists extending from grounded battery, winding of sequence switch magnet 120, D cam in positions 1 to 8, conductor 627, front contact and outermost left-hand armature of relay 604 to ground. Magnet 120 operates in this circuit and the sequence switch is moved into position 9. With the sequence switch in position 9, relay 606 operates in a circuit extending from grounded battery, right-hand winding of relay 606, conductor 605, middle left-hand armature and front contact of relay 604, conductor 628, cam K in position 9 to ground. The sequence switch now moves into position 10, magnet 120 being operated in a circuit extending from grounded battery, winding of magnet 120, D cam closed in position 9, conductor 610, front contact and inner left-hand armature of relay 606 to ground. In position 10 relay 606 is provided with a locking circuit through its own right-hand winding, inner right-hand armature and front contact of relay 606, conductor 607, cam I in position 10, conductor 608, back contact and outer left-hand armature of relay 609. The updrive magnet is now operated in a circuit extending from grounded battery, winding of magnet 124, closed contacts 613 of transfer switch 510, conductor 612, J cam closed in position 10, front contact and outer right-hand armature of relay 606 to ground over the outer left-hand armature and back contact of relay 609. If, at this time, the finder carriage 142 is positioned at a point above the normal position of plug 101 used in this connection, which may be the case, should the carriage have been employed in setting up another connection, the updrive magnet causes the finder carriage to travel to the top of the frame, whereupon the transfer switch is operated, causing the downdrive magnet 123 to be substituted for magnet 124 and contact 614 closed, whereupon the finder carriage moves downward.

In order to stop, the finder must find a 120 plug out of its seat and ground on the finder bank contact in the same position. As hereinbefore described, the contact 531 on the plug handler represented by 531 in Fig. 15 will close each time a position is found 125 where a plug is out of its seat. When a trunk, such as 500, is found with its associated plug out of its seat and ground on the finder bank contact 506, relay 609 operates in a circuit extending from ground on 130

the finder bank contact 506, brush 516, conductor 517, L cam in positions 10 and 11, conductor 533, closed contacts 531 of plug handler 532, conductors 534 and 615, left-hand winding of relay 609, cam O in positions 3 to 11 to battery and ground. Relay 609 in operating opens at its inner left-hand armature and back contact the locking circuit for relay 606, whereupon this relay releases. The release of relay 606 effects a circuit extending from grounded battery, winding of magnet 120, D cam in position 10, back contact and outer left-hand armature of relay 606 to ground. Magnet 120 operates in this circuit and moves the sequence switch into position 11. The selector magnet 121 now operates in a circuit extending from grounded battery, armature and back contact of plug magnet 125, winding of magnet 121, conductor 620, M cam in position 11, conductor 619, front contact and inner left-hand armature of relay 609 to ground. The selector magnet causes the bridge to move again across the multiple bank carrying the plug handler in search of the plug employed in the set up connection. When the plug handler strikes the plug, contact 531 is opened, which causes relay 609 to release whereupon the circuit for magnet 121 is opened and the movement of the bridge stopped.

Relay 609 releases causing the sequence switch magnet 120 to operate in a circuit extending from grounded battery, winding of magnet 120, F cam in positions 11 to 12½, conductor 625, back contact and inner left-hand armature of relay 609. Magnet 120 causes the sequence switch to be moved into position 13, whereupon the plug magnet 125 operates in a circuit extending from grounded battery, winding of plug magnet 125, conductor 519, C cam in positions 11 to 14, front contact and right-hand armature of relay 604, F cam in positions 11 to 12½, conductor 625, back contact and inner left-hand armature of relay 609 to ground. The plug magnet 125 in operating causes the plug to be seized as hereinbefore described.

When the sequence switch reaches position 13, the circuit for plug magnet 125 is opened at F cam in positions 4 and 11 to 12½. The pantograph is thereupon restored to normal, permitting the plug plunger 170 to remove the plug from the multiple. In restoring, magnet 125 causes the return magnet 122 to operate in a circuit extending from grounded battery, armature and back contact of magnet 125, winding of magnet 122, conductor 527, cam M in position 13, conductor 628, commutator M and its associated grounded brush. The return magnet 122 causes the bridge to be returned to its normal position carrying the plug with it.

In the normal position of the bridge,

ground on the Y commutator segment, conductor 534, F cam in positions 13 to 15, winding of magnet 120 to battery and ground, causes the sequence switch to be moved into position 15. While the sequence switch is moving from positions 13 to 15, plug magnet 125 is again energized causing the pantograph to be again actuated to restore the plug to its normal seat. The circuit for magnet 125 may be traced from grounded battery, winding of magnet 125, conductor 519, C cam in positions 11 to 14, front contact and right-hand armature of relay 604, F cam in positions 13 to 15, conductor 534 to ground on the Y commutator.

In position 15 of the sequence switch, relay 604 loses its locking circuit through the E cam closed in positions 1 to 15 and releases. With relay 604 unoperated, the sequence switch magnet 120 operates in a circuit extending from grounded battery, winding of magnet 120, cam E in positions 6 to 17, right-hand armature and back contact of relay 604, conductor 534, to ground on the Y commutator, causing the sequence switch to be moved into position 18 which is the "awaiting allotment" position.

At the end of each group of trunks, a segment D is provided on the commutator. The adjustment of the commutator brushes is such that a circuit to the overflow relay 630 is established through a brush in contact with the D segment to the relay before the sleeve brush loses contact with the sleeve segment of the last trunk in the group. The D segments are preferably metal inserts in the commutator which may be strapped together. Should it be desired to increase the size of the trunk group, the strap may be removed.

At the end of group selection, relay 606 releases as hereinbefore described, whereupon the D segments are grounded from ground at the inner left-hand armature and back contact of relay 606, cam N of the sequence switch in position 5, conductor 631 to the segments D on the commutator. When the contact brush of the overflow relay 630 strikes the grounded D segments, the overflow relay 630 is operated in a circuit extending from grounded battery, winding of relay 630, normal make-before-break contacts of relay 630, conductor 633, the brush associated therewith to ground on the D segments. Relay 630 in operating locks up by way of its make-before-break contacts, conductor 634, the brush associated therewith to ground on a feed bar OVF on the commutator 168 which is common to the entire bank. The operation of relay 630 prevents relay 609 from releasing, maintaining it operated in a circuit extending from grounded battery, O cam in positions 3 to 11, left-hand winding of relay 609, front contact and outer armature of relay 609, front contact and left-hand armature of relay 630 to ground. Relay 630

609 remaining operated, the plug is carried to the end of the bank to the overflow trunk. On the overflow trunk position the overflow relay brush moves off the OVF feed bar, 5 whereupon the locking circuit for relay 630 is opened and this relay releases. The release of relay 630 opens the locking circuit for relay 609 which restores, whereupon the plug handler places the plug in the overflow trunk 10 in the same manner as hereinbefore described in connection with the seizure of an idle outgoing trunk in a desired group. After discharging the plug, the bridge is returned to normal position and the sequence switch 15 moved to position 18 as for a regular selection.

Under normal conditions both plug carriers are in series and are used alternately. The waiting position of the sequence switch 20 is position 18 and the allotted position is position 1. When the sequence switch of either plug carrier reaches position 4, the other sequence switch is moved from the waiting position 18 to the allotted position 1. 25 The circuit effecting this change may be traced from grounded battery, winding of sequence switch magnet 635 located at the rear of the frame, B cam of the same switch in position 18, conductor 636, B cam of sequence switch on the front of the frame in positions 30 4 to 17 to ground. Should it occur that both carriers are engaged at the same time and reach position 18 together, the circuit is designed in such a manner that the carrier on 35 the front of the frame will be allotted first. This is accomplished by a circuit extending from ground, G cam of sequence switch on the rear of the frame in position 18, conductor 637, G cam of sequence switch on the front 40 of the frame closed in position 18, cam A of the sequence switch on the front of the frame in position 18, winding of magnet 120 to battery and ground. The operation of the magnet moves the sequence switch on the front 45 of the frame from the "waiting allotment" position 18 to the normal or allotted position 1.

A plug carrier on either side of the frame may be taken out of service if it is so desired 50 by actuating key 601 or key 638. If it is desired to remove the carrier on the front of the frame from service key 601 is actuated, placing ground on B cam of the sequence switch on the rear of the frame, so that when 55 this switch reaches position 18, a circuit for magnet 635 is closed causing the switch to move into position 1 immediately. The carrier may be taken out of service at any time. Any plug that happens to be in the multiple 60 at the time a key, such as 601, is actuated, will be taken down as required, as the disconnect circuit hereinbefore described is not disturbed by such operation of the key.

65 What is claimed is:

1. In a telephone exchange system in which the terminals of a group of incoming lines intersect the terminals of a group of outgoing lines and in which the terminals of incoming and outgoing lines are interconnected by means under the control of a common operating mechanism, the method of establishing connections which consists in causing the operating mechanism to select a connecting means individual to an incoming line, move it to a position for connecting with a desired 70 outgoing line, and cause it to interconnect the incoming line to which it is individual to a desired outgoing line, and returning the operating mechanism to its position of rest.

75 2. In a telephone exchange system in which the terminals of a group of incoming lines intersect the terminals of a group of outgoing lines and in which the terminals of incoming and outgoing lines are interconnected by means under the control of a common operating mechanism, the method of establishing connections which consists in causing the operating mechanism to select a connecting means individual to an incoming line, move it to a position for connecting with a desired 80 outgoing line, and cause it to interconnect the incoming line to which it is individual to a desired outgoing line, and returning the operating mechanism to its position of rest.

85 3. In a telephone exchange system in which the terminals of a group of incoming lines intersect the terminals of a group of outgoing lines and in which the terminals of incoming and outgoing lines are interconnected by means under the control of a common operating mechanism, the method of establishing connections which consists in causing the operating mechanism to select a connecting means individual to an incoming line, move it to a position for connecting with a desired 90 outgoing line, and cause it to interconnect the incoming line to which it is individual to a desired outgoing line, returning the operating mechanism to its position of rest and causing the operating mechanism to again 95 select the connecting means upon the termination of a call and to return it to its position of rest.

100 3. In a telephone exchange system in which the terminals of a group of incoming lines intersect the terminals of a group of outgoing lines and in which the terminals of incoming and outgoing lines are interconnected by means under the control of a common operating mechanism, the method of establishing connections which consists in causing the operating mechanism to travel vertically over a plurality of connecting means associated with the incoming lines, 105 select a certain one of said connecting means, and remove it from its normal position, carry the selected connecting means horizontally to a predetermined position and cause it to interconnect an incoming and outgoing line, returning the operating mechanism to its position of rest and at the termination of a call to cause the operating mechanism to again travel in a vertical plane and locate the normal position of the connecting means heretofore employed, to travel horizontally to the new position of the connecting means and remove it from association with the selected incoming and outgoing line terminals, and return it to its normal position.

110 4. In a telephone exchange system in which the terminals of a group of incoming lines intersect the terminals of a group of outgoing lines and in which the terminals of incoming and outgoing lines are interconnected by means under the control of a plurality 115

of operating mechanisms, the method of establishing connections which consists in causing one of said operating mechanisms to select a connecting means individual to an incoming line, move it to a position for connection with a desired outgoing line, cause it to interconnect the incoming line to which it is individual to a desired outgoing line, returning the operating mechanism to a position of rest, and positioning another of said operating mechanisms for serving a connecting means individual to another of said incoming lines.

5. In a switching mechanism, a multiple bank comprising a plurality of sets of incoming line terminals and a plurality of sets of outgoing line terminals, said sets of outgoing line terminals intersecting said sets of incoming line terminals, a plurality of means 15 for interconnecting any set of incoming line terminals with any set of outgoing line terminals at the intersections thereof, and means common to said interconnecting means for selecting an interconnecting means, for moving it to a position to interconnect said sets of terminals and for returning it to its normal position.

6. In a switching mechanism, a multiple bank comprising a plurality of sets of incoming line terminals and a plurality of sets of outgoing line terminals, said sets of outgoing line terminals intersecting said sets of incoming line terminals, a plurality of means for interconnecting any set of incoming line terminals with any set of outgoing line terminals at the intersections thereof, and a plurality of means common to said interconnecting means, any one of which is adapted to select an interconnecting means, to move 30 it to a position to interconnect said sets of terminals and return it to its normal position.

7. In a switching mechanism, a multiple bank comprising a plurality of sets of incoming line terminals and a plurality of sets of outgoing line terminals, said sets of incoming line terminals intersecting said sets of outgoing line terminals, movable plugs for cross connecting any set of incoming line terminals 45 with any set of outgoing line terminals, said plugs normally resting in plug seats, a plug handling device, means for causing said device to move said plug to the point of intersection of an incoming line terminal and a desired outgoing line terminal, means to cause said device to insert said plug at said intersection, and means for then restoring said device to its normal position.

8. In a switching mechanism, a multiple bank comprising a plurality of sets of incoming line terminals and a plurality of sets of outgoing line terminals, said sets of incoming line terminals intersecting said sets of outgoing line terminals, movable plugs for cross connecting any set of incoming line ter-

minals with any set of outgoing line terminals, said plugs normally resting in plug seats, a plug handling device, means for causing said device to move said plug to the point of intersection of an incoming line terminal and a desired outgoing line terminal, means to cause said device to insert said plug at said intersection, means for then restoring said device to its normal position, and means operative following the termination 70 of a connection for again causing said plug handling device to select said plug and to return it to its seat.

9. In a switching mechanism, a multiple bank comprising a plurality of sets of incoming line terminals and a plurality of sets of outgoing line terminals, said sets of incoming line terminals intersecting said sets of outgoing line terminals, removable plugs on either side of said bank for cross connecting 80 any set of incoming line terminals with any set of outgoing line terminals, said plugs normally resting in plug seats, a pair of plug handling devices, one on either side of said bank, means for causing either of said devices 85 to select a plug, move said plug to the point of intersection of an incoming line terminal and the desired outgoing line terminal and to insert said plug at said intersection, and means for then restoring the operated device 90 to its normal position.

10. In a switching mechanism, a terminal bank having sets of incoming and outgoing line terminals therein, a plug normally resting in a plug seat at one end of said bank, and a plug handler adapted to seize said plug and remove it from its seat in response to a call incoming to a set of incoming line terminals and deposit it in said bank at another position to interconnect said sets of incoming and 100 outgoing line terminals.

11. In a switching mechanism, a terminal bank having sets of incoming and outgoing line terminals therein, a plurality of plugs normally resting in plug seats at one end of said bank, and each individual to a set of incoming line terminals, and a plug handler adapted to select the plug individual to a set of incoming line terminals to which a call has been extended, remove it from its seat 110 and carry it to another position on said bank to interconnect said set of incoming line terminals with a set of outgoing line terminals.

12. In a switching mechanism, a terminal bank having sets of incoming and outgoing line terminals therein, a plurality of plugs normally resting in plug seats at one end of said bank, and each individual to a set of incoming line terminals, and a plug handler adapted to select the plug individual to a set of incoming line terminals to which a call has been extended, remove it from its seat 120 and deposit it at another position in said bank to interconnect said set of incoming line 125 terminals.

terminals with a set of outgoing line terminals and at the termination of the call to return the plug and deposit it in its normal seat.

13. In a switching mechanism, a terminal bank having sets of incoming and outgoing line terminals therein, a plug normally resting in a seat at one end of said bank, a carriage, a plug handler carried thereby, and means responsive to a call incoming to a set of incoming line terminals for causing said carriage to position said plug handler in operative relation with said plug, whereupon said plug handler seizes said plug, removes it from its normal seat and deposits it at another position in said bank to interconnect a set of incoming and outgoing terminals.

14. In a switching mechanism, a terminal bank having sets of incoming and outgoing line terminals therein, a plurality of plugs normally resting in plug seats at one end of said bank and each individual to a set of incoming line terminals, a carriage, a plug handler carried thereby, and means responsive to a call incoming to a set of incoming line terminals for causing said carriage to hunt for the plug individual to said set of terminals, whereupon said plug handler seizes said plug, removes it from its seat and deposits it at another position in said bank to connect said set of incoming line terminals with a set of outgoing line terminals.

15. In a switching mechanism, a terminal bank having sets of incoming and outgoing line terminals therein, a plurality of plugs normally resting in plug seats at one end of said bank and each individual to a set of incoming line terminals, a carriage, a plug handler carried thereby, means responsive to a call incoming to a set of incoming line terminals for causing said carriage to hunt for the plug individual to said set of terminals, means for causing said plug handler to seize said plug and remove it from its seat, and means for causing said plug handler to be disengaged from said carriage and moved to another position in said bank, whereupon said second mentioned means again operates to cause said plug handler to deposit said plug at the new position to interconnect the set of incoming line terminals with a set of outgoing line terminals.

16. In a switching mechanism, a multiple bank comprising a plurality of sets of incoming line terminals and a plurality of sets of sets of outgoing line terminals, said sets of incoming line terminals intersecting said sets of outgoing line terminals, movable plugs for each of said incoming line terminals for cross connecting any set of incoming line terminals with any set of outgoing line terminals, said plugs normally resting in plug seats, a plug handling device, means responsive to a call incoming to a set of incoming line terminals for causing said plug handling device to be moved into engagement with the plug asso-

ciated with said incoming line terminals, means for causing said device to seize said plug and remove it from its seat, means for moving said device with said plug to the point of intersection of the calling incoming line terminals and a desired set of outgoing line terminals, means for causing said devices to insert said plug at said intersection, means for then restoring said device to its normal position, and means responsive to the termination of a connection for causing said device to be moved to a position adjacent the vacated plug seat and thence to the new position of the plug to seize said plug and return it to its seat.

17. In a switching mechanism, a terminal bank having sets of incoming and outgoing line terminals therein, a plug normally resting in a plug seat at one end of said bank, a plug handler adapted to seize said plug and remove it from its seat in response to a call incoming to a set of incoming line terminals and deposit it at another position in said bank to interconnect a set of incoming and outgoing line terminals, means for returning said plug handler, and means responsive to the termination of a call for causing said plug handler to hunt for said plug and return it to its normal seat.

18. In a switching mechanism, a terminal bank having sets of incoming and outgoing line terminals therein, a plug normally resting in a plug seat at one end of said bank, a plug handler for said plug, means responsive to a call incoming to a set of incoming line terminals for causing said plug handler to seize said plug and remove it from its seat, a bridge adapted to engage said plug handler and move it to another position in said bank, whereupon said plug is deposited in said bank to interconnect a set of incoming and outgoing line terminals, means for returning said bridge and said plug handler, and means responsive to the termination of the call for causing said bridge to again carry said plug handler into engagement with said plug, whereupon said plug is removed from its position and returned to its normal seat.

19. In a switching mechanism in which plugs are employed as connecting means, a terminal bank, a plurality of plug carriers serving said bank in the establishing of telephone connections, and means for causing said plug carriers to serve said bank in a certain sequence.

20. In a switching mechanism in which plugs are employed as connecting means, a terminal bank, a plurality of plug carriers serving said bank in the establishing of telephone connections, means for causing a certain one of said plug carriers to serve said bank upon the initiation of a call, and means operative when the plug carrier employed reaches a certain position in serving said bank for causing another of said plug

carriers to be placed in readiness to serve said bank upon the initiation of another call.

21. In a switching mechanism, a terminal bank, incoming line terminals therein, other line terminals therein, plugs for each of said incoming line terminals positioned on either side of said bank and adapted to interconnect said incoming line terminals with said other terminals, a plug carrier on each side of said bank serving said plugs, means responsive to a call on an incoming line terminal for causing a plug carrier on one side of said bank to move to and seize a plug corresponding to the calling line, and means operative when the last mentioned carrier reaches a certain stage in extending a connection for preparing the other of said plug carriers to serve a plug corresponding to another incoming line terminal on which a call may be initiated.

22. In a switching mechanism in which plugs are employed as connecting means, a terminal bank, a plurality of plug carriers serving said bank in the establishing of telephone connections, means for causing said carriers to serve said bank in a certain sequence, and means for disabling one of said carriers whereby another of said carriers handles all calls incoming to said bank.

23. In a switching mechanism in which plugs are employed as connecting means, a terminal bank, a plurality of plug carriers serving said bank in the establishing of telephone connections, means for causing said carriers to serve said bank in a certain sequence, and manually controlled means for disabling one of said carriers whereby another of said carriers handles all calls incoming to said bank.

24. In a switching mechanism in which plugs are employed as connecting means, a terminal bank, a plurality of plug car-

riers serving said bank in the establishing of telephone connections, means for causing said carriers to establish connections in turn, and means for disabling one of said carriers whereby another of said carriers handles all calls incoming to said bank and the disabled carrier takes down the connections it was instrumental in establishing.

25. In a switching mechanism in which the terminals of a group of incoming lines intersect the terminals of a group of outgoing lines and in which connections are made by plugs, a team of plug carriers, and means for causing said team of plug carriers to serve said switching mechanism to interconnect sets of incoming and outgoing line terminals at their points of intersection.

26. In a switching mechanism in which the terminals of a group of incoming lines intersect the terminals of a group of outgoing lines and in which connections are made by plugs, a team of plug carriers, and means for causing said team of plug carriers to serve said switching mechanism to interconnect sets of incoming and outgoing line terminals at their points of intersection and to unmake said connections.

27. In a switching mechanism in which the terminals of a group of incoming lines intersect the terminals of a group of outgoing lines and in which connections are made by plugs, a plug carrier on one side of said switching mechanism, a plug carrier on another side of said switching mechanism, and means for causing both of said plug carriers to serve said mechanism in turn to interconnect sets of incoming and outgoing line terminals at their points of intersection.

In testimony whereof, I have signed my name to this specification this 13th day of July, 1927.

WILLIAM G. BLAUVELT.
